UNITED STATES PATENT OFFICE.

GEORGE W. WATSON, OF NASHUA, NEW HAMPSHIRE, ASSIGNEE TO NASHUA CARD GUMMED AND COATED PAPER COMPANY, OF NASHUA, NEW HAMPSHIRE, A CORPORATION OF MASSACHUSETTS.

WRAPPING-MACHINE.

1,110,090.

Specification of Letters Patent. Patented Sept. 8, 1914.

Application filed May 13, 1912. Serial No. 693,264.

To all whom it may concern:

Be it known that I, GEORGE W. WATSON, of Nashua, in the county of Hillsboro and State of New Hampshire, have invented 5 certain new and useful Improvements in Wrapping-Machines, of which the following is a specification.

This invention relates to wrapping machines, and particularly to mechanism for 10 associating wrappers with articles, such as loaves of bread to be inclosed in such wrappers. In other words, the present invention does not include any particular means for completing the wrapping operation, but 15 refers only to means for assembling sheets of paper or other material with the articles, such as loaves of bread, in such manner that the size of the sheets will be controlled by the size of the article to be wrapped.

One of the objects of the invention is to 20 provide improved mechanism whereby the articles are brought into contact with the wrapping material, and then advanced, carrying the material along so that said material partially incloses the article before it is cut off.

Further objects of the invention are to 25 provide improvements which I shall now proceed to describe and claim.

Of the accompanying drawings, Figure 1 30 is a side elevation, partly in section, of sufficient of the machine to illustrate the invention. Fig. 2 is a plan view, omitting some of the parts shown at the top of Fig. 1. Fig. 3 is a diagrammatic elevation of one of 35 the intermittently rotatable disks, and some of the members carried thereby. Fig. 4 is an end elevation from the left of Fig. 2, on a larger scale, and omitting some of the 40 parts of the mechanism to avoid confusion. Fig. 5 is a detail sectional elevation similar to a portion of Fig. 1. Fig. 6 is a detail view illustrating the mechanism for operating the paper grippers.

Similar reference characters indicate the same or similar parts wherever they occur.

A portion of a suitable frame for the machine is indicated at 10 in Fig. 1. Fixedly supported by such frame are two stud shafts 45 11, 12, the stud 12 having a toothed disk 13 mounted to rotate thereon. On the other stud 11 is mounted a notched disk 14 through the intermediary of a sleeve 15. In other

words, the sleeve 15 is rotatably mounted on the stud 11 and has the notched disk keyed 55 or otherwise secured to its inner end. Keved or otherwise secured to the outer end of the sleeve 15 is a gear 16 (Fig. 2).

A countershaft 17 (Fig. 1) carries two pinions 18 which mesh with the gear 16 and 60 the toothed disk or gear 13, the object of this countershaft and the pinions being to insure rotation of the disks 13 and 14 in unison.

Each disk 13 and 14 is provided with a plurality of arms or brackets 19 (four being 65 illustrated carried by each disk), said arms or brackets 19 being suitably formed to support the parts hereinafter described as carried by said arms or brackets. Each arm or bracket 19 has connected thereto a carrier 70 member 20, said carrier members being arranged in pairs, as best shown in Fig. 4, the two members of each pair facing each other so as to receive and support the opposite ends of an article. The articles will be hereinafter referred to as loaves because the machine is primarily designed to wrap loaves 75 of bread. The term "loaf" or "loaves," however, is to be understood as employed for the purpose of description only and not 80 of limitation. The members 20 are of course spaced apart farther than shown in Fig. 4, in which figure the center space is contracted so as to reduce the width of that figure. Each pair of members 20 constitutes a carrier for a loaf.

Mounted to oscillate on the sleeve 15 is a hub, 21 (Fig. 2), said hub having an arm 22 (Figs. 1 and 3) having a spring-pressed pawl 23 adapted to engage either one of 90 four notches 24 in the disk 14. To the arm 22 is connected one end of a pitman 25, the other end of which is connected to a crank pin 26 carried by the shaft 28 which is adapted to receive power from any suitable 95 source. As the shaft rotates, the arm 22 is oscillated by the pitman 25 so as to impart a step-by-step rotation to the disk 14 in the direction of the arrow on Figs. 1 and 3, each step being one-fourth of a rotation of the 100 disk. Through the sleeve 15, gear 16, pinions 18 on the shaft 17, corresponding step-by-step rotation is imparted to the disk 13. To prevent backward motion, a suitable spring-pressed detent may be employed, such 105 as illustrated at 29 in Fig. 1.

The loaves of bread are placed by hand or otherwise on a belt conveyer 30, a portion of the upper stretch of said belt having a suitable support 31. Said belt runs on a pulley 32 which is suitably supported, the shaft of said pulley having a band wheel 33 engaged by a belt or band 34 driven by a pulley on the shaft 28. The direction of travel of said belt is indicated by the arrow 10 in Fig. 2.

When each loaf reaches the proper position, it is pushed from the belt into the two members 20 of a carrier, when said members are in the position *a* indicated in Figs. 15 1, 3 and 5.

To enable the operation to be more readily understood, the letters *a*, *b*, *c*, and *d* are employed to indicate the four successive positions occupied by the carriers. The mechanism for transferring or pushing each loaf from the conveyer belt to position *a* comprises an arm or arms 35 pivoted to the frame at 36, and having a roll 37 which is engaged by a cam 38 on the main-shaft 28. A bar 39 at the lower end of the arm or arms 35 (Figs. 1 and 2) carries plates or pushers 40 mounted at the inner ends of pins slidably mounted in the bar 39, and having springs 41 so that the action of said 30 pushers or plates 40 will be a yielding one.

Carried by the bar 39 so as to swing therewith are two stop plates 42, 43, which control the positioning of each loaf by the traveling conveyer 30. As shown in Figs. 1 and 35 2, the plate 42 projects considerably farther toward the path of rotation of the carriers than the plate 43, so that when the said bar 39 and plates 42, 43 are in the position shown in Fig. 2, the plate 43 will stop the advance 40 of a second loaf, and when the said bar and plates are swung outwardly so as to remove the plate 43 from arresting position, the plate 42 will stop the loaf on the carrier 30 in such position that when the pushing 45 mechanism next swings back to the position shown in Figs. 1 and 2, the loaf that has been stopped by the plate 42 will be transferred to the carrier members 20 occupying position *a*. The returning or outward 50 movement of the pushing devices is effected by means of a plunger 44 (Fig. 1) acted upon by a suitable spring 45.

It is desirable that the loaf shall be held firmly in its carrier as it travels somewhat 55 rapidly from position *a* to position *b*, and it is also desirable if no loaf has been transferred to a carrier that no movement shall be imparted to the carrier disks 13, 14. I will now proceed to describe the mechanism 60 whereby these results are accomplished.

A hub 46 having arms 47, 48, is carried by the inner end of a rock-shaft 49 (Figs. 2 and 3), mounted in a sleeve 50 carried by the disk. There are eight of these mechanisms, four carried by each disk 13, 14, and

a description of one will suffice for all. Fig. 3 illustrates the mechanisms carried by disk 14, and it is to be understood that similar mechanisms are carried by the disk 13. Each rock-shaft has a cam lug or arms 51 which is acted upon by a spring-pressed plunger 52 so as to hold the arm 51 and the rock-shaft and its two arms 47, 48 either in the position shown at the right of Fig. 3, or in the other positions *b*, *c*, and *d*. The 70 arm 47 extends outwardly past the open side of a carrier member 20 and the arm 48 projects into the path of a loaf that is being pushed into a carrier, so that when a loaf is pushed into position, the bottom of such loaf 75 acting against arm 48 will push said arm inwardly and rock the shaft 49, the side arm 47 closing in against the upper side of the loaf to hold it, the cam lug 51 snapping past the plunger 52 so that the said plunger 52 80 will act through the parts described to cause the arm 47 to bear yieldingly against the loaf. It is to be understood at this point that each loaf is held by two of the side arms 85 47, as will be apparent from Fig. 2 of the 90 drawings. The position occupied by the side arms 47 when grasping a loaf is best illustrated in Fig. 1.

In order to open the grasping arms so as to admit a new loaf after one has been carried around and discharged from the carrier, as hereinafter described, each arm 48 is provided with a cam 53 (Fig. 3) which engages a fixed pin 54 (see also Fig. 1), so that just as each pair of grasping devices 95 moves past position *d* toward position *a*, said cams 53 riding over the fixed pins 54 will oscillate the rock-shafts sufficiently to cause the cam lugs 51 to snap past plungers 52 in order to re-assume the position *a* indicated in Fig. 3. This same mechanism is utilized to prevent rotation of the disks if no loaf has been introduced to position 100 *a*. To this end, each rock-shaft carries also a notch-closer, or bridge 55 adapted to prevent the engagement of the pawl 23 of arm 22 with a notch 24 of the disk 14. These 105 notch closers or bridges 55 are carried only by the rock-shafts that are supported by the disk 14. Referring to position *d* in Fig. 110 3, it will be understood that as cam 53 moves over the end of fixed pin 54, it causes the shifting of the rock-shaft and its arms over so that the member 55 crosses the notch 24. It will remain in this position if no loaf is 115 introduced so as to cause a shifting back of the rock-shaft and its arms to grasp a loaf, and therefore said member 55 will prevent the pawl 23 from entering the notch, and consequently no step rotation will be 120 imparted to the two disks until a loaf has been pushed in from the full line position *a* of Fig. 3 to the dotted line position of that figure. Such pushing in will shift the rock-shaft and its arms to the position illus- 125 130

trated in Fig. 1 in position *a*, thus opening the notch 24 to permit the pawl 23 to engage said notch so that the next operation of the pitman 25 will impart one-fourth rotation, as indicated by the dotted arrow in Fig. 3.

To support and guide the portion of each loaf intermediate its ends as it is being pushed into the members 20, a plate 56 (Figs. 1 and 2) is supported by a suitable fixed bar 57, and to bridge the space between the conveyer belt and said guide plate 56, I provide a bridge plate 58 carried by a suitably supported bar 59.

15. The paraffined paper or other suitable wrapping material α is led from a suitable source of supply, not shown, under a gravity roll 60 (Fig. 1) over a guide roll 61 to position to be engaged between movable 20 grippers 62 and stationary gripping members or studs 63 supported by the bracket arms 19 on both disks. The gripping devices are duplicates of each other, and a description of one will suffice for all, there 25 being four carried by each disk. Each movable gripper 62 is carried by the outer end of an arm of a rock-shaft 64 having a suitable bearing at 65, and provided with a toothed segment 66 (Figs. 4, 5, and 6). The 30 rock-shaft has a projection 67 adapted to be acted upon by a spring-pressed plunger 68 to hold the rock-shaft with the grippers 62 in their open or closed position. Mounted to reciprocate in a portion of the bracket 35 arm 19 is a bar 69 having a rack or toothed portion engaging the toothed segment 66 of the rock-shaft, the other end of said bar being beveled as at 70. The operation of these portions of the machine will be more 40 readily understood presently.

Referring to Figs. 1 and 5, a stationary bar or knife to cooperate with the movable knife is shown at 71, said bar or knife 71 being supported by bracket arms 72 keyed 45 on the inner ends of the two fixed studs 11, 12. The movable knife 73 is carried by arms 74 (only one of said arms being shown), pivoted at 75 and having an arm 76 provided with a roll 77 engaging a cam 50 groove 78 in a disk 79 carried by the main shaft 28.

Each arm 74 of the movable knife has a cam plate 80 adapted, when the knife descends to the position shown in Figs. 1, 5, 55 and 6, to engage a curved or cam surface of the arm which carries the gripper 62, so as to press said gripper to the position shown in Fig. 6, snapping the cam projection 67 past the spring plunger 68 so that 60 the said spring plunger will cause the gripper arm to yieldingly grasp the paper α between it and the stationary gripping member or stud 63. Lugs 81 secured to the fixed bracket arms 72 are provided with stops 65 82 which cooperate with stops 83 carried by

the knife arms 74 to limit the lowermost position of the movable knife. Owing to the cam plates 80, the movable knife, when it descends and cuts the paper, closes down grippers 62 (one at each edge of the strip 70 of paper α), the grippers which are so operated being those which are adjacent the carriers that are in position *a*. It is desirable that the gripper adjacent the carrier that is in position *b* shall be opened at about this 75 same time. This operation of opening the grippers 62 when they reach position *b* is effected by the knife 73 engaging the beveled ends 70 of the rack bar 69 (see Fig. 5), so as to thrust said bars in a direction to cause 80 their teeth which are in engagement with the toothed segment 66, to turn the rock-shafts so as to open the pair of movable grippers that have been closed, the projection 67 snapping past the spring plungers 85 68 so that the latter will hold the rock-shafts 64 with the movable grippers open and in position to be closed down again upon edge portions of the strip of paper when position *a* is again reached. The descent of the knife bar cuts off a wrapper section α' , as shown in Fig. 1, which is then draped over the loaf, hanging down on each side thereof, the loaf being then in position 90 to be removed from the carrier, as will now 95 be described.

Above that portion of the mechanism occupied by the carriers when in position *b* is a chute or "well" along which may be arranged or mounted end folders of the type 100 illustrated in the application filed January 11, 1911, Serial No. 602,062, by H. A. Sevigne. The rear wall 84 of this chute or well is preferably spring mounted, and the lower section 85 of the front wall is shown 105 as hinged at 86, and having an arm 87 which engages a pin 88 to limit the inward position to which said section 85 can be pressed by a spring plunger 89. A wing 90 pivoted at 91 to arms 92 (only one arm being shown) 110 pivoted at 93 and the lower position of which is limited by a stop pin 94, is pressed toward the path of movement of the loaf by a spring 95 mounted in a recess in the arm 92 and acting upon a pin projecting 115 rearwardly from said wing 90. This yieldingly mounted wing 90 is for the purpose of bridging the space between the lower edge of the rear wall 84 and the loaf carrier, so as to insure the wrapper section α' being 120 held in smooth condition while the loaf and the wrapper section α' are being pushed upwardly, as hereinafter described. But said wing 90 must be shifted out of position when the knife rises so that the paper α can 125 be drawn directly upwardly when a loaf is being transferred from position *a* to position *b*. This is because the knife must be independently lifted by its cam high enough so 130 that it will not bear upon the paper as it

is being drawn as just described. For this reason, the wing 90 is carried by the arms 92, which arms 92 are engaged by the arms 74 of the movable knife when the latter 5 swings upwardly to the dotted line position shown in Fig. 1, so as to lift said arms 92 and the wing 90 to the dotted line position indicated. Afterward, as the knife descends, it deflects the paper downwardly, 10 drawing from the gravity roll 60, because the grippers 62 are still holding the far end of the paper at the left hand side of the loaf occupying position *b* until the knife has descended to position to cut and at the same 15 time act upon the two rack bars to open the movable grippers so that the wrapper section *w'* is now entirely free, but draped over the loaf as shown.

To next lift the loaf in position *b*, and its 20 associated wrapper *w'* into and through the chute and past the end folders thereof, I employ lifters 96 which pass upwardly through the spaces provided between the two members 20 of each carrier. It is for 25 the purpose of enabling the lifters 96 to pass to elevate the loaves successively, that the spaces are provided, as best shown in Fig. 4, between the duplicate members carried by the two intermittently rotated disks. 30 Each lifter 96 is carried by an arm 97 mounted on a rod 98 carried by chains 99, each rod having an arm 100 provided with a roll 101, said chains being suitably supported by brackets 102 (Fig. 2), said brackets 35 having path guides 103, 104 for the ends of the rod 98 and the rolls 101 respectively. The details of this mechanism for guiding the lifters 96 in the proper path are not illustrated herein as the same form no part 40 of this invention, and may be the same or substantially the same as illustrated and described in the Sevigne application referred to.

The operation of the several parts having 45 been described in connection with the construction thereof, description of the operation of the machine as a whole will not be necessary.

As has been stated, the present invention 50 relates particularly to means for associating wrappers with articles such as loaves of bread, the invention not including any specific means for completing the wrapping. In Fig. 1 of the drawings, however, I have 55 illustrated at 105 and 106 means for performing further wrapping operations, said means being similar to the helical corner folders illustrated and claimed in the Sevigne application referred to. It is to 60 be understood, however, that I may use any other mechanism for completing the wrapping operation.

With such means for completing the wrapping, the machine comprises an inter- 65 mittently rotatable carrier as described,

means for severing a wrapper from a web or strip and placing it partially around the article in the carrier while the latter moves from position *a* to position *b*, independent means such as the folders 111, 112 in the 70 chute or well for performing further wrapping operations, and a transerrer comprising the lifters 96 for removing the article and its associated wrapper *w'* from the carrier to the said chute or well alongside of 75 which are located the independent wrapping means.

By comparing Figs. 1, 2 and 4, it will be seen that each pair of carrier members 20, 20 constitute a pocket capable of receiving 80 a loaf, and permitting the top of the loaf to project from the pocket any distance according to the height of the loaf. Furthermore, each such pocket has an opening clear through it, including its bottom, to 85 permit the passage of a lifter 96 which constitutes a transerrer. The members 20, 20 provide the two ends of the pocket and what there is of its bottom and one side wall, while two movable arms 47 provide the 90 other side wall. When a pocket moves from position *a* (Fig. 1) to position *b*, the wrapper material is draped over the outside of this pocket as well as the loaf contained therein, and therefore there is no such pressure upon the loaf tending to crush it, as would be the case if the wrapper material were pushed into the pocket using the loaf as the pusher. As the pocket starts from 95 position *a*, the first strain of overcoming the 100 inertia of the supply roll or gravity roll 60, is borne by the grippers 62, 63 which, then moving in a curved path, causes a gradual increase in the speed of pull of the paper, a portion of the strain of which is borne by 105 the members 47 of the pocket. In brief, the wrapper is draped not only over the loaf, but also over the pocket, thereby reducing liability of a soft loaf being crushed by the pressure resulting from paper tension. To enable such draping to be effected, there are, as shown in Fig. 1, spaces or recesses between the several pockets of the series of such area as to permit the complete 110 draping described, the grippers being in 115 such spaces or recesses, and the cutter also moving into them successively. The amount of wrapper material drawn from the supply roll will, of course, depend upon the extent 120 to which the top of the loaf projects from the pocket. Therefore, since the grippers have a fixed location, relatively to the pockets and the cutter operates always in the same location, the length of each section of 125 wrapper material will be controlled by the height of the particular loaf to be wrapped in that section. As already explained, this control of size is effected with no such pressure upon the loaf as to crush it.

Owing to the arrangement described, in- 130

cluding especially the feature of the pockets having normally open clear passageways through them, the lifters 96 are able to move in a path intersecting the path of the pockets so as to transfer each loaf and its draped wrapper section to and through the chute 84, 85, for further folding or wrapping, by a smooth continuous motion without disturbing the relationship of the loaf and wrapper section during the transfer.

I claim:

1. A wrapping machine comprising an intermittently rotatable carrier, means for holding a web or strip of wrapping material in position relatively to an article in the carrier to cause the article as it moves from one position to another to advance the web or strip and to be partially inclosed therein, a cutter to sever the web or strip after it has been advanced by the article, independent means for performing further wrapping operations, and a transfferer for removing the article and its associated wrapper from the carrier to the said independent wrapping means.
2. A wrapping machine comprising an intermittently rotatable series of carriers, means for holding a web or strip of wrapping material in position relatively to an article in each carrier to cause each article as it moves from one position to another to advance the web or strip and to be partially inclosed therein, a cutter to sever the web or strip after it has been advanced by each article, independent means for performing further wrapping operations, and means for removing the articles and their associated wrappers successively from the carrier to the said independent wrapping means.
3. A wrapping machine comprising an intermittently rotatable series of carriers, means for pushing articles to be wrapped successively into said carriers, means for holding a web or strip of wrapping material in position relatively to an article in the carrier to cause the article as it moves from one position to another to advance the web or strip and to be partially inclosed therein, a cutter to sever the web or strip after it has been advanced by the article, independent means for performing further wrapping operations, and means for removing the articles and their associated wrappers successively from the carrier to the said independent wrapping means.
4. A machine of the character described, having an intermittently movable series of carriers for the articles to be wrapped, recesses being provided between the carriers of the series, grippers movable with the carriers, said grippers being mounted in said recesses to grasp a strip of wrapping material at one side of the article in a carrier, and means operable in said recesses for severing the strip at another side of the article.
5. In a machine of the character described, an intermittently rotatable series of carriers, wrapper grippers movable with the carriers, means for actuating said grippers to cause them to grasp the wrapper material at one step of rotation, a cutter for severing the material at another step of rotation, and means for causing the release of said material at the last mentioned step of rotation.
6. In a machine of the character described, means for assembling an article with a wrapper having an area proportioned to the size of said article, said means comprising a movable carrier having a receptacle for the article, grippers for one end of a strip or web of wrapper material, said grippers being located at one side of said receptacle, and means on the other side of said receptacle, and means on the other side of said receptacle for severing the strip or web when the article reaches a predetermined position.
7. In a machine of the character described, means for assembling an article with a wrapper having an area proportioned to the size of said article, said means comprising a movable carrier having a receptacle for the article, grippers for one end of a strip or web of wrapper material, said grippers being located at one side of said receptacle, and movable with the carrier, and means on the other side of said receptacle for severing the strip or web when the article reaches a predetermined position.
8. A machine of the character described, having a movable carrier for an article to be wrapped, means for draping a wrapper section over the top and sides of the carrier and the article therein, and means for preventing movement of the carrier if no article is contained therein.
9. A machine of the character described, having an intermittently movable series of carriers for the articles to be wrapped, each of said carriers comprising a pair of receivers for the opposite ends of an article, means for associating a wrapper section with each article, folding mechanism, and a transfferer movable through the space between the said end receivers to carry the article to the folding mechanism.
10. A machine of the character described, having a pair of disks geared to rotate in unison, means for intermittently rotating said disks, carrier members connected with said disks and formed to receive the opposite ends of an article, means for associating a wrapper section with each article, and a transfferer mounted independently of said disks and movable in a path intersecting the path of the carriers.
11. In a machine of the character described, an intermittently rotatable series of carriers, each carrier comprising two members facing each other to support the ends of

an article, said members having normally clear spaces between them, means for associating a wrapper section with each article supported in said members, and a trans-
5 ferrer mounted independently of the carriers and movable in a path intersecting the path thereof.

12. A machine of the character described, having two disks geared to rotate in unison, 10 one of said disks being notched, an arm having a pawl adapted to successively engage the notches of said disk, means for oscillating said arm, article carriers supported by said disks, means for associating a wrapper 15 section with each article supported by said carriers, the machine including the disks and carriers having a normally clear passageway, and a trans-
20 ferrer mounted independently of the disks and movable through said pas- sageway.

13. A machine of the character described, having an intermittently movable carrier for an article to be wrapped, a conveyer movable past said carrier, a pusher for trans-
25 ferring an article from the conveyer to the carrier while the latter is in one position of rotation, and means for applying a wrapper section over the carrier and the outer surface 30 of the article in said carrier during movement of the carrier to its next position of rotation.

14. A machine of the character described, having an intermittently movable carrier for an article to be wrapped, a conveyer mov-
35 able past said carrier, a pivoted arm having spring pusher plates for transferring an article from the conveyer to the carrier while the latter is in one position of rotation, means for swinging said arm and its pusher 40 plates, and means for applying a wrapper section over the carrier and the outer surface of the article in said carrier during movement of the carrier to its next position of rotation.

45 15. A machine of the character described, having an intermittently movable carrier for an article to be wrapped, a conveyer movable past said carrier, a pivoted arm having stops to arrest articles on the con-
50 veyer, means for oscillating said arm to insert an article in a carrier while the latter is in one position of rotation, and means for applying a wrapper section over the carrier and the outer surface of the article in said 55 carrier during movement of the carrier to its next position of rotation.

16. In a machine of the character de-
scribed, an intermittently rotatable series of carriers, movable holders to retain articles 60 in the carriers when moving from one position to another, and means for draping wrapper sections over the outer surfaces of the article held in the carriers and over the sides of the carriers during the rotative

movements of the carriers from one position 65 to another.

17. In a machine of the character de-
scribed, an intermittently rotatable pair of disks connected to move in unison, said disks having article carriers with open sides, arms 70 extending past said open sides and adapted to bear upon articles in the carriers, means for opening and closing said arms, and means for associating a wrapper section with each article that is being moved by the car-
75 riers.

18. A machine of the character described, having an intermittently movable series of carriers for the articles to be wrapped, each of said carriers comprising a pair of re-
80 ceivers for the opposite ends of an article, said receivers having open sides, a rock shaft adjacent each carrier, and having two arms, one extending past the open side of the re-
ceiver, and the other extending under the 85 bottom of the receiver to be actuated by an article inserted in the latter, means for shifting and holding the rock shafts and their arms in either one of two different positions, and means for associating a wrapper section 90 with each article in a carrier.

19. A machine of the character described, having an intermittently movable carrier for an article to be wrapped, means for controlling the movements of the carrier according 95 to the presence or absence of an article in said carrier, and means for draping a wrapper section over the top and sides of the carrier and the article therein.

20. A machine of the character described, having an intermittently movable carrier for an article to be wrapped, a notched disk, a pawl adapted to successively engage the notches of the disk, means for actuating said pawl, means for controlling the operation of 105 said pawl according to the presence or absence of an article in the carrier, and means for draping a wrapper section over the top and sides of the carrier and the article therein.
110

21. A machine of the character described, having a pair of disks, one of which is pro-
vided with notches, means for causing said disks to move in unison, article carriers sup-
115 ported by said disks, rock shafts adjacent the carriers, each rock shaft adjacent the notched disk having a notch closer, means for controlling the position of said notch closer according to the presence or absence of an article in the carrier, and means for 120 associating a wrapper section with an article in the carrier.

22. A machine of the character described, having an intermittently movable series of carriers for articles to be wrapped, rock 125 shafts adjacent the carriers, and having grippers positioned to grasp the end of a strip of wrapping material at one side of

an article in a carrier, and means for operating the rock shafts when the carriers move from one position to another to first close the grippers on the wrapping material, 5 and then raise them.

23. A machine of the character described, having an intermittently movable series of carriers for the articles to be wrapped, a rock shaft adjacent each carrier, said rock 10 shaft having a gripping arm and a toothed segment, means for actuating the rock shafts in one direction to close the grippers, racks engaging the toothed segments and adapted to actuate the rock shafts in the other direction to open the grippers, and means for 15 associating a wrapper section with each article in a carrier.

24. A machine of the character described, having an intermittently movable series of 20 carriers for the articles to be wrapped, a rock shaft adjacent each carrier, and having a gripping arm and a toothed segment, a spring-pressed plunger for holding the rock shaft in either one of two positions, means 25 for actuating the rock shafts to shift them from one position to the other, and means for associating a wrapper section with an article in the carrier.

25. A machine of the character described, 30 having an intermittently movable series of carriers for articles to be wrapped, a rock shaft adjacent each carrier, said rock shaft having a gripping arm and a toothed segment, a rack bar engaging said toothed segment, a spring-pressed plunger for holding the rock shaft in either one of two positions, means 35 for associating a wrapper section with each article in a carrier, means for actuating the rock shafts to close the grippers, 40 when the carrier is in one position, and means for shifting the rack bars when the carriers reach another position to cause the grippers to open.

26. A machine of the character described, 45 having an intermittently movable series of carriers for articles to be wrapped, a rock shaft adjacent each carrier, said rock shaft having a gripping arm and a toothed segment, a rack bar engaging said toothed segment, a spring-pressed plunger for holding the rock shaft in either one of two positions, means 50 for associating a wrapper section with each article in a carrier, means for actuating the rock shafts to close the grippers, 55 when the carrier is in one position, and means for shifting the rack bars when the carriers reach another position to cause the grippers to open, the last mentioned means comprising a knife bar, the ends of the rack 60 bars being beveled to be engaged by the said knife bar.

27. A machine of the character described, having an intermittently movable series of carriers for the articles to be wrapped, a

rock shaft adjacent each carrier and having 65 a gripping arm and a toothed segment, a spring-pressed plunger for holding the rock shafts in either one of two positions, a movable knife bar having a cam plate to engage each gripper arm to close it, a rack bar engaging the toothed segment and having a beveled end to be engaged by the knife bar, and means for associating a wrapper section with each article in a carrier. 70

28. A machine of the character described, 75 having an intermittently movable series of carriers for articles to be wrapped, means for associating a wrapper section with each article in a carrier, a chute in position to receive the associated articles and wrappers, a 80 yielding wing for bridging the space between the carrier and a wall of the chute, and means for shifting said wing out of the path of a carrier that is moving from one position to another. 85

29. A wrapping machine comprising an intermittently rotatable carrier, means for drawing a web or strip of wrapping material, and placing it partially around an article in the carrier while the latter moves 90 from one position to another, said means including a knife which completes said partial wrapping, and means for raising the knife out of contact with the web when the carrier is moving from one position to another. 95

30. A machine of the character described, having an intermittently movable series of carriers for the articles to be wrapped, each of said carriers comprising a pair of receivers for the opposite ends of an article, a 100 space being provided between the receivers of the pairs, means for severing a wrapper from a web or strip and placing it partially around an article in the carrier while the latter moves from one position to another, 105 and lifters movable through the space between the receivers to remove the articles and their associated wrapper sections from the carriers.

31. A wrapping machine comprising a rotatably mounted pocket for the article to be wrapped, said pocket having a normally clear passageway through it, means for assembling an article and a wrapper section in the pocket, a stationary chute having 110 wrapper folding devices, said chute being outside of the path of rotation of the pocket, and a transerrer movable through the pocket and chute. 115

32. A wrapping machine comprising a rotatable series of pockets, means for draping wrapping material over the pockets and articles contained therein, wrapper folding devices mounted outside of the path of rotation of the pockets, and a transerrer for 120 carrying the articles and draped material from said pockets to said folding devices, said transerrer being mounted to move in a 125

path intersecting the path of movement of the pockets, said pockets having passageways to permit the transerrer to move through them.

33. In a machine of the character described, a rotatably mounted pocket for the article to be wrapped, means for draping wrapping material over the top and sides of the pocket and an article contained therein, 20 a cutter for severing the material after it is draped, and independent means for performing further wrapping operations.

34. In a machine of the character described, a rotatable series of pockets with 15 intervening spaces, means for draping wrapping material over the tops and sides of the pockets and articles contained therein as

they rotate, and a cutter mounted to operate successively in said spaces.

35. In a machine of the character de- 20 scribed, a rotatable series of pockets with intervening spaces, grippers in said spaces, said grippers being adapted to grasp one end of a length of wrapping material and draw said material over each pocket as it 25 rotates, and a cutter mounted to operate successively in the spaces.

In testimony whereof I have affixed my signature, in presence of two witnesses.

GEORGE W. WATSON.
